Patented May 18, 1915.

UNITED STATES PATENT OFFICE.

IRA P. CLARK, OF DECATUR, ILLINOIS, ASSIGNOR OF ONE-FOURTH TO WILLIAM B. HUNTER, OF HAGARSTOWN, ILLINOIS.

WATER-CLOSET.

1,140,252.

Specification of Letters Patent. Patented May 18, 1915.

Application filed May 20, 1914. Serial No. 828,831.

To all whom it may concern:

Be it known that I, IRA P. CLARK, citizen of the United States, residing at Decatur, in the county of Macon and State of Illinois, have invented certain new and useful Improvements in Water-Closets, of which the following is a specification.

This invention relates to apparatus for flushing closets and the like where an intermittent or periodical discharge of a volume of water is desirable.

The object of my invention is to provide an automatic flushing device for closets and the like in which the operation of filling the tank and of discharging its contents are effected without any of the gurgling, singing or other noises caused by flow of water through gradually opening or closing valves.

The invention is illustrated in the accompanying drawings, wherein:

Figure 1 is a perspective view of a closet with the tank partly broken away and showing my present improvements; Fig. 2 is a longitudinal detailed sectional view of the supply valve; Fig. 3 is a vertical sectional view of the tank valve.

In carrying out my invention, I provide a supply pipe 1 which leads to the bottom of the tank and opens into a cylinder or chamber 3 constituting the casing of the tank valve. The said tank valve consists preferably of a rubber ball 4 secured upon the lower end of a rigid stem 5 having a float 6 at its upper end. The said stem passes through a guide consisting of a bracket 7 secured to and projecting above the upper end of the casing 3 and the valve seat is provided with a collar or short sleeve 8 which is screwed into the top of the casing 3 and depends within the same as clearly shown. In the side of the said casing I provide a minute vent opening 9 which serves to relieve the pressure upon the valve when the supply valve is closed.

The closet bowl 10 is provided with a seat 11 which is hingedly mounted thereon in the usual manner and is equipped with a lever 12 which extends rearwardly therefrom and is provided with a forked end adapted to fit around an operating rod 13 and bear against an adjustable stop 14 on said rod. A spring 15 is coiled around the said rod between the bottom of the tank 16 and the said stop and serves to normally hold the said rod in a lowered position with the seat 11 slightly

raised. When the seat is occupied the lever 12 will be swung upward and the spring compressed and it will be readily understood that by securing the stop 14 by means of a set screw 17 at any desired point upon the operating rod the tension of the spring 15 may be regulated as desired. Inasmuch as the end of the lever 12 is forked it will readily swing away from the operating rod when the seat is swung up into an approximately vertical position for any purpose. The said operating rod 13 extends upwardly within the tank through a guide 18 which may be of any convenient or preferred form and is illustrated as consisting of a metallic sleeve or tube secured in the tank. At the upper end of said guide is a bracket 19 upon which is fulcrumed a lever 20 having one end pivoted to the upper end of said operating rod 13, while the opposite end of the said lever is secured to the flushing valve 21 which is illustrated in the form of a tube or sleeve provided at its lower end with spaced rods or guides fitting within the outlet or flushing pipe 22. It will be readily understood that when the said sleeve or tube 21 is lowered it will fit closely over the end of the outlet pipe 22 and consequently will prevent flow through the same, but when the valve is lifted the water in the tank will at once be discharged.

The lower end of the operating rod 13 is bent laterally as shown at 23, to extend under and be secured to the lower end of the stem 24 of the supply valve. The supply valve proper consists of a disk or other body 25 rigid with the upper end of the said stem and adopted to seat upon a partition 26 in the valve casing 27 so that normally flow through said valve casing will be prevented. A spring 28 is provided between the valve disk or body 25 and the upper side of the casing so as to hold the valve normally seated, acting in this respect with the spring 15 coiled around the operating rod.

It is thought that the operation and advantages of my improved device may be readily understood from the foregoing description taken in connection with the accompanying drawings.

Normally the closet seat is slightly raised and the tank is empty, the supply valve being closed. When the seat is occupied the lever 12, as before stated, will lift the operating rod 13 and the said rod will trans-

mit its upward movement directly to the valve stem 24 so that the supply valve will be opened. At the same time the lever 20 will be rocked upon its fulcrum and the 5 flushing valve closed so that water flowing into the tank will be held in the same until the seat is released. As the water flows into the tank the float 6 will rise with the level of the water and consequently will draw 10 the valve 4 up against the seat presented by the lower end of the collar 8. The water flows past the valve 4 and escapes through the said collar 8 until the required quantity has entered the tank when the valve 4 will 15 be drawn against its seat. As the water rises in the casing 3 it will trap a small quantity of air between the top of the casing and the upper portion of the water so that an air space will be provided which 20 will cushion the water and coact with the same to prevent any hammering in the operation of the device. As the valve 4 approaches the seat 8 it will have no effect whatever upon the water and consequently 25 the whistling or singing heard with the ordinary slowly closing valves will be overcome. When the valve gets close to its seat it will move quickly against the same so as to cut off the flow positively and rapidly and 0 without any disagreeable noises. While the seat is occupied the pressure of the water upon the interior and exterior of the tank valve casing 3 will be equal and consequently the vent 9 will have no effect in permitting unseating of the tank valve, but 35 when the seat is released the springs 15 and 28 will at once expand and cause the supply valve to close and the flushing valve to open and the water in the tank will then be 40 discharged through the outlet pipe 22 as above stated. The closing of the supply valve will of course prevent inflow of water against the tank valve and the vent 9 will then serve to relieve the pressure below 45 the said valve so that it will move down-

wardly and away from its seat without causing any blowing or whistling noises. This vent should be exceedingly small and preferably not over one-thirty second of an inch 50 in diameter.

It will be readily noted that the several parts of my improved closet are exceedingly simple in their construction and in their arrangement so that the apparatus may be installed at a low cost and will not be apt 55 to get out of order so that the cost of maintenance and repair will be of no moment.

Having thus described the invention, what is claimed as new is:

The combination of a tank, a supply pipe 60 leading into the tank, an outlet from the tank, a flushing valve within the tank arranged to open or close said outlet, means for establishing or arresting flow through the supply pipe and simultaneously actuating the flushing valve, a tank valve chamber rising within the tank over the supply pipe and provided with a minute permanently open vent in its side near its lower end, a collar depending from the top of the 70 tank valve chamber and spaced from the wall of the same, said chamber being otherwise unobstructed and the space between the collar and the wall of the chamber being restricted transversely of the chamber 75 but somewhat extended longitudinally thereof, a single valve in the tank valve chamber adapted to seat against the lower end of the collar, a stem rising from said valve through the collar, a guiding support 80 for said stem above the tank and valve chamber, and a float on said stem above said support, the diameter of the stem being very slight relative to the collar.

In testimony whereof I affix my signature 85 in presence of two witnesses.

IRA P. CLARK.
